PNEUMATIC WELL DRILL

Roy E. Kitching, Pasadena, Calif.

Application August 27, 1934, Serial No. 741,563

7 Claims. (Cl. 255—4)

This invention relates to pneumatic tools and particularly pertains to tools of the type in which fluid pressure actuated mechanism is operated while submerged in liquid; the invention more specifically appertaining to pneumatically operated well drills in which a liquid or mud is circulated through the well bore during drilling operations.

An object of the invention is to provide a well drill of the above character embodying a shank fitted with a compressed air operated cutting tool and which is designed to be carried on a revolvable tubular stem through which circulating liquid or mud is delivered to the well bore, in which means are provided whereby the liquid or mud may be conveyed from the stem and discharged adjacent the cutting tool on the shank apart from the air operated mechanism in the shank; a particular object being to provide a construction whereby the liquid or mud may be conveyed exteriorly of the drill shank substantially throughout the length thereof, so as to obviate the necessity of forming the shank with bores or ducts for conveying the liquid or mud, thereby simplifying the construction of the drill and effecting a great economy in its manufacture.

Another object is to provide a drill embodying the above features in which the liquid conveying element is so formed as to serve as a reinforcement of the drill shank, and also act as a shield to protect the drill shank during operation of the drill.

Another object is to provide construction whereby a free flow of the liquid or mud from the stem along the shank to the cutting tool will be insured, and whereby clogging of the liquid passages will be practically obviated.

Another object is to provide a pneumatic drill with a water jacket whereby liquid may be caused to flow over the external surface of the drill shank in such manner as to effect a cooling action thereon.

A further object is to provide a simple and effective method of forming a drill shank with a liquid conduit extending substantially throughout the length thereof.

With the foregoing objects in view together with such other objects and advantages as may subsequently appear, the invention resides in the features, and in the construction and arrangements, and in the parts and combinations of parts, hereinafter described and claimed, and illustrated by way of example, in the accompanying drawing; it being understood, however that the invention as herein set forth is not to be limited to

the exact construction shown, as the construction may be subject to various changes and modifications to meet varying conditions and accordingly the following specification of the invention is to be considered in its broadest sense and to include equivalents coming within the meaning of the appended claims.

In the drawing:

Fig. 1 is a view of the drill as seen in side elevation: 10

Fig. 2 is a detail in cross section taken on line 2—2 of Fig. 1:

Fig. 3 is a view of the drill in longitudinal section with parts shown in elevation as seen on the line 3—3 of Fig. 2: 15

Fig. 4 is a detail in longitudinal section taken on line 4—4 of Fig. 2:

Fig. 5 is a detail in cross section taken on line 5—5 of Fig. 3:

Fig. 6 is a detail in cross section taken on line 6—6 of Fig. 3:

Fig. 7 is a detail in section taken on the line 7—7 of Fig. 3:

Fig. 8 is a view in section as seen on the line 8—8 of Fig. 3: 25

Fig. 9 is a section and end view of the drill as seen from the lower end thereof on the line 9—9 of Fig. 3.

Referring to the drawing more specifically, A indicates generally the shank of a pneumatic well drill which is here shown as comprising a series of interconnected sections including an upper end section 10, a lower end section 11, and intermediate sections 12, 13, 14, and 15 connecting the end sections 10 and 11. The upper end section 10 is connected to the intermediate section 12 by a screw-threaded joint 16, the sections 12 and 13, 13 and 14, 14 and 15, 15 and 11 are interconnected by telescoped joints, as shown in Fig. 3. 30

The lower end section 11 carries a cutting tool or bit 17 which is demountably attached to a stem 18 reciprocally supported in the end section 11 and extending through a seal 19 carried on the latter, the upper end portion of the stem 18 being provided with a collar 20 located in a recess 21 formed in the end section 11 against which and the bottom of the recess 21 is interposed a spring 22 which acts to normally maintain the cutting tool or bit 17 in a retracted position. The upper end of the stem 18 is squared as indicated at 23 and passes through a guideway 24 formed in the intermediate section 15 whereby the stem 18 is held against rotation on its axis. 40

Mounted in a bore 25 formed in the interme- 55

date section 13 is a reciprocal hammer 26 arranged to impact on the upper end of the stem 18 when in operation. The hammer 26 is here shown as carried on a piston rod 27, the upper end portion of which passes through a packing gland 28 and is connected to a piston 29 arranged in a cylinder 30 carried in the intermediate shank section 13. The upper end of the cylinder 30 is formed in the section 12 of the shank in which is mounted a conventional valve 31 for controlling the intake and exhaust of air under pressure to and from the cylinder 30 on opposite sides of the piston 29 as is common in pneumatic tool operating mechanism.

15 The section 12 and the walls of the cylinder 30 are formed with the usual ports and passages for effecting the intake and exhaust of air under pressure not necessary to be here shown but which includes an intake passage 32 leading from the 20 upper end portion of the section 12 centrally thereof and communicating through a port 33 with the valve 31, and also including an exhaust passage 34 leading from a chamber 35 in the upper end of the section 12 and communicating 25 with the valve 31.

An intake pipe 36 leading from any suitable source of fluid pressure supply such as a reservoir of compressed air is connected to the intake passage 32 and connecting with the chamber 30 35 is an exhaust pipe 37 which encircles the intake pipe 36 and leads to any suitable point of discharge.

The upper end portion of the end section 10 is adapted to be connected to a tubular stem 38 35 on which the drill is carried and through which the intake and exhaust pipes 36 and 37 extend.

40 The tubular stem 38 serves as a means for effecting rotation of the drill and for this purpose is revolved in any suitable manner as is common in oil-well drilling operations. The stem 38 also serves as a means for conveying a circulating liquid or mud into the well bore which is effected by connecting the upper end of the stem 38 to a source of liquid or mud supply under pressure 45 in the usual manner.

An important feature of the present invention resides in the provision of a means for conveying liquid or mud from the stem 38 downwardly along the drill shank A and effecting its discharge adjacent the lower end of the latter and contiguous the cutting tool or bit 17. This means is here shown as embodying a tubular metallic shell 40 which encircles or encompasses the shank A and extends substantially throughout 50 the length of the latter. The shell 40 is spaced from the outer periphery of the shank A to provide a space 41 constituting a passage through 55 which liquid or mud may flow from the upper to the lower end portion of the drill shank exteriorly of the latter. The shell 40 may be affixed relative to the shank A in any desired manner but is here shown as secured thereto at its ends through the medium of collars 42 and 43 formed on the upper and lower end sections 10 and 11 60 respectively of the shank, which collars have telescoped engagement with the ends of the shell 40 and hold the latter in spaced concentric relation to the shank A.

As a means for affording a communication between the interior of the stem 38 and the space 41 interiorly of the shell 40 the end section 10 of the shank is formed with a series of passages 51 which lead downwardly from the upper end of the shank and open to the sides of the latter into the space 41 as particularly shown in Fig. 3.

As a means for permitting discharge of the liquid or mud from the passage 41 the section 11 is formed with a series of passages 52; these passages being here shown as fitted with nozzles 53 inclined downwardly and inwardly towards opposite sides of the cutting tool 17 whereby on discharge of liquid or mud through the section 11 a series of jets thereof will be directed against the cutting tool in such fashion as to effect a cleaning action thereon during operation.

By thus encompassing the shank A with the shell 40 ample space is provided for the passage of the usual circulating liquid or mud without the necessity of forming the shank proper with ducts or bores for this purpose. Furthermore, the shell 40 serves as a reinforcement to strengthen the shank and also affords a protection thereto.

As a means collectively holding the shell 40 and the several shank sections together in a fashion which will permit of their ready assemblage and disassembly, a series of tie rods 54 are employed, which rods extend longitudinally of the space 41 and have their end portions passed through the end sections 10 and 11 and fitted with nuts 55 screwed thereon. The intermediate shank sections 12, 13, 14, and 15 are formed with radial webs 56 having longitudinal channels 57 in which the tie rods 54 seat as shown in Fig. 7 which webs serve as guides to facilitate assemblage of the several shank sections in their proper relative positions as also serve in co-operation with the tie rods to form partitions or walls separating the space 41 into a series of passages as shown in Figs. 6 and 7 whereby accumulation and packing of solids in 20 the space 41 during operation is prevented.

As a means for protecting the seal 19, nozzles 53 and nuts 54 against injury, a guard cap 58 is secured to the lower section 11 by a threaded ring 59 and which cap is formed with openings 60 disposed opposite the discharge ends of the nozzles 53. The cap is preferably formed in halves as shown in Fig. 9 to permit it being put in place and removed without necessitating detachment of the bit 17.

In the operation of the invention the drill shank A with its attached shell 40 and the cutting tool 17 thereon, is secured to the tubular drill stem 38 with the air intake pipe 36 and the air exhaust pipe 37 connected in place and extending through the drill stem to their respective points of termination. The drill stem is lowered into the well and rotated in the usual manner common in rotary well-drilling operations and during rotation thereof the cutting tool 17 is reciprocated by the action of compressed air on the piston 29 and hammer 26 through the medium of the air-controlled mechanism as is common in pneumatic tool operations. A suitable liquid or mud is forced into the well bore under pressure through the tubular stem 38 by means of the usual pump; the liquid or mud being delivered from the stem 38 through the passages 51 into the space or passage 41 around the drill shank and thence delivered from the lower end of the shank through the passages 52 and nozzles 53 into the well bore from whence it flows and is circulated in the usual manner. The incoming liquid or mud in passing down the passage 41 in contact with substantially the entire outer periphery of the drill shank will act to absorb and carry away a portion of the heat generated by the operation of the hammer and the compressed air operated mechanism thus effecting a cooling action on the drill.

I claim:

1. In a pneumatic well drill, a shank having end sections, a tubular liquid conveying stem carrying said shank, a shell encompassing said shank and having telescoped engagement with the end sections thereof, there being a space between said shell and shank opening adjacent one end of said shank, passages in one end portion of said shank affording communication between the interiors of 5 said stem and shell, and tie rods in said space interconnecting said end sections and detachably holding said shell in place.
2. In a pneumatic well drill, a shank having end sections and embodying a plurality of telescopically interconnected intermediate sections, a shell encompassing said shank and telescopically connected at its ends to the end sections of said shank, and tie rods interconnecting the end sections of said shank.
3. In a pneumatic well drill, a shank having end sections embodying a plurality of intermediate sections telescoped together, a shell encircling said shank, and connections leading between said shell and shank connecting the end sections of 10 said shank for securing said sections and shell against disengagement.
4. In a pneumatic well drill, a shank having end sections and embodying a plurality of interconnected intermediate sections, webs on said intermediate section, a shell encircling said shank, a telescoped connection between said shell and each end section of said shank, and tie rods connecting the end sections of the shank for securing said sections and shell against disengagement, 15 said tie rods engaging said webs.
5. In a pneumatic well drill, a shank, a cutting tool carried on one end of said shank, a collar encircling said shank adjacent the end thereof carrying said tool having liquid discharge passages

therethrough, nozzles arranged to direct liquid inwardly from said passages toward the opposite sides of said tool, a shell encircling said shank connected at one end to said collar, there being a space between said shell and shank extending 20 substantially throughout the length of the latter communicating with said passages, and means for directing a stream of liquid into the upper portion of said space.

6. In a pneumatic well drill of the class described, a shank, a cutting tool carried on the lower end of said shank, a collar on the upper end portion of said shank, a shell encircling said shank forming a liquid conduit extending substantially throughout the length of said shank 25 exteriorly thereof, said shell encircling said collar and connected thereto, a collar on the lower end portion of said shank encircled by the lower end portion of said shell and to which said shell is connected, said last named collar being formed with inclined passages, and nozzles leading from 30 said passages, opening toward the sides of said cutting tool.

7. In a pneumatic well drill of the class described, a shank having end sections and embodying a plurality of telescopically interconnected intermediate sections, webs extending longitudinally of said intermediate sections, a shell encircling said shank in spaced relation thereto and telescopically engaging said end sections and 35 abutting endwise thereagainst, and tie-rods seating on said webs and extending longitudinally thereof for collectively securing said shank sections and shell together, said tie rods abutting the inner periphery of said shell and co-acting with 40 said webs to divide the space between said shank and shell into a plurality of longitudinally extending passages.

ROY E. KITCHING.
